UNITED STATES PATENT OFFICE.

MELVIN L. STONE, OF LAWRENCE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed January 4, 1924. Serial No. 684,435.

To all whom it may concern:

Be it known that I, MELVIN L. STONE, a citizen of the United States, and a resident of Lawrence, in the county of Essex and 5 State of Massachusetts, have invented an Improvement in Feeler Mechanisms for Looms, of which the following description, in connection with the accompanying drawings, is a specification, like characters on the 10 drawings representing like parts.

This invention relates to feeler mechanisms for looms whereby the operative condition of the loom is changed when the filling is substantially exhausted in the shuttle.

15 In accordance with the present invention, the feeler mechanism is provided with a lock which prevents premature call for replenishment of filling and yet permits the feeler to effect replenishment of filling when 20 that in the active shuttle is substantially exhausted.

In feeler mechanisms of the side swipe type, that is, where the feeler itself is moved 25 to effect replenishment of filling, it sometimes happens that the feeler will engage a working supply of filling on a detecting beat and by the impulsive contact will fail to be held from movement longitudinally of 30 the filling carrier and prematurely call for a change of filling even though a working supply is present in the shuttle. One of the objects of the present invention, therefore, is to provide a feeler mechanism where- 35 in the feeler is prevented from prematurely calling for a change of filling and is freed for movement longitudinally of the filling carrier when the filling approaches a condition of substantial exhaustion but not prior 40 thereto.

In the drawings:

Fig. 1 is a plan view showing a feeler mechanism embodying the present invention with the feeler engaged with a working 45 supply of filling on a detecting beat;

Fig. 2 is a view similar to that of Fig. 1 but showing the relation of parts when the feeler engages the filling in the shuttle which has approached to a condition of substantial exhaustion;

Fig. 3 is a perspective view showing a feeler mechanism embodying the present invention;

Fig. 4 is a longitudinal section on the line 55 4—4 of Fig. 1;

Fig. 5 is an enlarged perspective view of certain parts of the locking mechanism, some of the features being broken away; and

Fig. 6 is a detached detail showing the trackway of the switch controlling mechanism.

It has not been deemed necessary herein to show the means for changing the operative condition of the loom through the feeler mechanism, such, for instance, as re- 65 replenishment of filling, because the details of such mechanism form no part of the present invention.

The feeler of the present illustrated form of the invention is of the inclined type which 70 enters the shuttle in a direction inclined to the longitudinal axis thereof on a detecting beat and is displaced longitudinally along the filling carrier by the forward pressure when the filling is substantially exhausted to 75 thereby call for replenishment, and while the advantages of the present invention are clearly manifested in this type of feeler mechanism, it is to be understood that the invention is not necessarily limited thereto 80 but may be employed in a feeler mechanism wherein other means than the forward pressure may displace the feeler laterally along the filling carrier when filling is substantially exhausted.

85 Inasmuch as the present invention pertains particularly to the feeler mechanism and the feeler lock, the loom parts are not herein shown, except in so far as will enable one skilled in the art to associate the feeler mechanism with the loom.

The feeler stand 1 is provided with a slot 2 through which passes a bolt 3 by which the feeler stand may be adjustably secured to the loom frame, as usual.

95 The rear of the feeler stand 1 has a guide-way formed by the upstanding portions 4 and 5 to provide a guide for a slide or laterally movable member 6 having a slot 7 through which the feeler 8 extends, and connected to the slide 6 is a transmitter 9 by which movement of the slide under call of the feeler may effect replenishment of filling.

100 The forwardly extending stem portion 10 of the feeler passes through a bearing or swivel block 11 mounted upon the bracket 12 secured to the feeler stand, and between the swivel block 11 and the bridge 13 which is secured to the feeler is a spring 14 normally tending to move the feeler into its 110

rearward feeling position. The parts thus far described may be substantially the same as those more fully shown and described in the patent to Edward S. Stimpson, No. 5 1,309,226, July 8, 1919, and need no further description.

The filling carrier 15 is of the usual type and carries the filling 16 when the filling carrier is in the shuttle, but the shuttle box 10 with its slotted front wall and the shuttle with its similarly slotted front wall are not herein shown because they are now well understood and of the usual type to enable the feeler to enter the shuttle on a detecting beat 15 to feel for the filling in the shuttle.

In accordance with the present invention a lock is provided to restrain the feeler from sideswipe movement prematurely and to release the feeler to such movement when the 20 filling approaches but before it reaches substantial exhaustion.

Connected to the feeler is a lock operating member which is moved by the feeler on detecting beats and through such movement 25 effects both the locking and unlocking positions of the feeler lock.

In the present instance, the lock operating member comprises an arm 17 pivotally secured to the feeler at 18 and extending 30 frontwardly therefrom. The downturned front end portion 19 of the arm carries a switch 20 which is pivotally connected to the arm at 21. Preferably the lock operating member is adjustable in length by a screw 35 22 which may be properly manipulated to lengthen or shorten the arm by means of a thumb nut 23.

The present invention provides a trackway for the switch, and as shown in the present instance the trackway 24 is formed in the feeler stand and has a central portion 25 which provides between the walls 26 of the trackway and the central portion a part at each side the central portion in which the switch is adapted to travel when moved by the feeler on a detecting beat, as will herein-after more fully appear.

Pivottally mounted, preferably on the feeler stand 1, is the rocker arm 27, Fig. 5, its pivot being shown as formed by a stud 28 extending upwardly into the feeler stand at one side of the trackway. Rising from the rocker 27 at opposite sides of its pivotal support 28 are the studs 29 and 30 each of 55 which carries a collar 31, 32 secured thereto as by a pin 33, 34, and each of the collars 31, 32 has a tooth 35, 36 adapted at times to be engaged by the switch to effect rocking movement of the rocker 27, and slots 37, 38 60 are formed in the feeler stand for limiting the rocking movement of the rocker under the impulse of the switch.

The rocker has connected thereto at its end 39 a locking pin 40, the rear end portion of 65 which extends through the front wall 5 of

the rear bearing of the slide 6 and is adapted to engage the slide 6 when in operative position to prevent movement thereof. In the present instance of the invention, the rear end portion of the locking pin 40 engages a recess or hole 41 formed in the slide 6, as best illustrated in Fig. 4. From the construction thus far described it will be apparent that when the locking pin 40 is engaged with the slide, the latter is held from movement in its guideway and thus replenishment of filling is prevented.

In the present instance of the invention, the locking pin 40 has a downturned end 42, Fig. 4, which enters the slot 43, Fig. 5, 80 formed in the end of the rocker 27, although other forms of action might be utilized.

The collars 31, 32 carried by the rocker 27 have their toothed portions 35 and 36 positioned as indicated in Fig. 6, that is, such toothed portions extend slightly beyond the central member 25 and the wall 26 of the trackway 24 in position to be engaged by the switch 20 under conditions presently to be described. To provide for the projection 90 of the tooth 35, 36 into the trackway 24, the central member 25 and the wall 26 of the trackway are undercut or provided with a cover plate, as shown, to permit the tooth to extend into the path of the switch, and yet protect the parts from accidental disturbance.

The switch 20 has its end portions 44, 45 extending in opposite directions, as indicated, to form lock actuating teeth, and the spring 46 normally acts upon the switch to turn the latter or tend to turn it in a clockwise direction, shown in Figs. 1, 2 and 3.

When a working supply of filling is present in the shuttle on a detecting beat 105 and the feeler is moved frontwardly thereby, as indicated in Fig. 1, the arm 17 is likewise moved frontwardly thereby moving the switch frontwardly in the trackway 24 until the end 45 of the switch 110 extends beyond the front end portion of the central member 25 of the trackway, as indicated in Fig. 1. As the lay goes back after its frontward beat and the parts are located relatively, as in Fig. 1, the arm 17 115 likewise retreats and the switch passes along the trackway at the opposite side of the central member 25. If at such time the feeler lock is not in operative position and engaged with the slide 6, the toothed end 45 120 of the switch will engage the tooth 36 of the collar 32 and turn the rocker 27 to set the lock. On subsequent detecting beats, so long as a working supply is present in the shuttle, the switch 20 will continue to move 125 in the different paths indicated by the arrows in Fig. 1 and the lock will remain in locking position. When the filling approaches substantial exhaustion but prior thereto the feeler will be moved frontward-

ly a less distance than it is under a working supply of filling in the shuttle, as indicated in Fig. 2, and the switch 20 will not pass beyond the front end of the central member 25, so that as the lay goes back the switch 5 will travel back in the same path in which it traveled frontwardly, as indicated by the double arrow, Fig. 2, and on its rearward movement the toothed end portion 45 of the 10 switch will engage the tooth 35 of the collar 31 and cause the rocker 27 to be rocked in a clockwise direction, Figs. 1, 2 and 5, thereby withdrawing the lock 40 from its locking position and freeing the feeler for movement longitudinally along the filling carrier 15 or longitudinally of the shuttle, a movement that will take place when the filling later reaches a degree of substantial exhaustion.

20 Movement of the feeler along the filling carrier or longitudinally of the shuttle is utilized in the present instance to effect replenishment of filling substantially as in the Edward S. Stimpson patent hereinbefore mentioned, and on the next detecting beat with a working supply of filling in the shuttle, the feeler will again be moved frontwardly to carry the switch 20 frontward of the central member 25 and the switch will 25 then retreat as the lay goes back in the opposite pathway, as indicated in Fig. 1. As the switch moves backwardly under the conditions stated, it will engage the tooth 36 of the collar 32 thereby rocking the rocker 27 to again set the lock, and thereafter the lock will remain set until the filling approaches a predetermined degree of substantial exhaustion.

From the construction described, it will 40 be seen that the present invention provides a feeler with a lock which is operated from the feeler to both set and unlock the lock, and while the mechanism shown and described is found to be a good practical form 45 of the invention, it is obvious that changes may be made within the scope of the mechanical equivalents without departure from the present invention, since applicant believes himself to be the first in the art to 50 provide a feeler mechanism with a feeler lock which is operated by the feeler to trip the lock when filling approaches a degree of substantial exhaustion, and he also believes himself to be the first in the art to 55 provide a feeler lock which is actuated by the feeler to both lock and unlock the feeler.

What is claimed is:

1. In a feeler mechanism for looms, the combination of an inclined side swipe feeler, a lock normally acting to prevent premature side swipe movement of the feeler, a lock cooperating member carried by the feeler and movable thereby in a prescribed path on each detecting beat until the filling reaches a predetermined degree of exhaustion and thereupon being moved in a different path as the feeler goes back that the lock tripping member may trip the lock and free the feeler to side swipe movement when the filling is substantially exhausted. 70
2. In a feeler mechanism for looms, the combination of a side swipe feeler, a lock for preventing premature side swipe movement of the feeler, and a lock operating member moved by the feeler for both setting and tripping the lock. 75
3. In a feeler mechanism for looms, the combination of a side swipe feeler, a lock for preventing premature side swipe movement of the feeler, and a lock operating member moved in one direction for setting the lock, and moved in another direction by the feeler for tripping the lock when the filling reaches a predetermined degree of exhaustion. 80
4. A feeler mechanism for looms, comprising a side swipe feeler, a laterally movable slide through which the feeler extends, a lock acting upon the slide to prevent its lateral movement, and a lock operating member which is actuated by the feeler for disengaging the lock from the slide when the filling approaches substantial exhaustion. 90
5. In a feeler mechanism for looms, the combination of a feeler mounted for movement in a direction longitudinally of the shuttle to effect replenishment of filling, a lock normally acting to prevent movement of the feeler longitudinally of the shuttle to call for replenishment of filling, and a lock operating arm permanently connected to the feeler and movable thereby in a normal path on each detecting beat until the filling has reached a predetermined degree of exhaustion and thereupon being movable in an abnormal path by the feeler to trip the lock and free the feeler to movement longitudinally of the shuttle when the filling is substantially exhausted. 95
6. In a feeler mechanism for looms, the combination of a feeler mounted for movement towards and from the loom and in a direction longitudinally of the shuttle to effect replenishment of filling, a lock normally acting to restrain movement of the feeler longitudinally along the filling carrier, a lock operating member mounted on the feeler and movable thereby in a normal path until the filling reaches a predetermined degree of exhaustion and thereupon being movable in an abnormal path by the feeler to trip the lock and free the feeler to movement along the filling carrier when the feeler detects substantial exhaustion of the filling in the shuttle. 115
7. In a feeler mechanism for looms, comprising, in combination, a feeler mounted for movement longitudinally along the filling carrier in the shuttle to initiate replen- 120
8. In a feeler mechanism for looms, comprising, in combination, a feeler mounted for movement longitudinally along the filling carrier in the shuttle to initiate replen- 125
9. In a feeler mechanism for looms, comprising, in combination, a feeler mounted for movement longitudinally along the filling carrier in the shuttle to initiate replen- 130

ishment of filling, a lock to prevent such movement of the feeler prematurely, and a lock operating member connected to and movable by the feeler to trip the lock through feeler movement when the filling in the shuttle approaches substantial exhaustion.

8. A feeler mechanism for looms, comprising, in combination, a feeler mounted for movement longitudinally along the filling carrier in the shuttle to initiate replenishment of filling, a lock to prevent such movement of the feeler prematurely, and a lock operating member and switch movable by the feeler to trip the lock when the filling in the shuttle approaches substantial exhaustion.

9. In a feeler mechanism for looms, the combination of a feeler mounted for movement along the filling carrier in the shuttle when the filling is substantially exhausted to effect replenishment of filling, a swinging arm connected to the feeler and movable therewith, a switch device for swinging the arm as it is moved by the feeler, and a lock constructed and arranged to be tripped by feeler induced

movement of the arm when the filling approaches substantial exhaustion.

10. A feeler mechanism for looms, comprising, in combination, a feeler supported to enter the shuttle in a direction inclined to the longitudinal axis thereof and to be moved along the filling carrier by the forward pressure to effect replenishment of filling, a slide through which the feeler extends, a lock for engaging the slide to prevent movement of the feeler along the filling carrier, and means actuated by feeler movement when the filling approaches substantial exhaustion to trip the lock and free the feeler to movement along the filling carrier.

11. In a feeler mechanism for looms, the combination of a feeler, a feeler lock to prevent premature replenishment of filling by the feeler, a switch, a trackway for the switch, means associated with the feeler for moving the switch in the trackway and rendered effective to trip the lock when the feeler detects a near approach to substantial exhaustion of the filling in the shuttle.

In testimony whereof, I have signed my name to this specification.

MELVIN L. STONE.
